UNITED STATES PATENT OFFICE

JOHN LANZ, OF NEW HAVEN, CONNECTICUT, ASSIGNOR, BY MESNE ASSIGNMENTS, TO THE A. C. GILBERT COMPANY, OF NEW HAVEN, CONNECTICUT, A CORPORATION OF MARYLAND

ELECTRIC FAN

Application filed July 29, 1926. Serial No. 125,702.

This invention relates to electric fans, and more particularly to a fan of the oscillating type so constructed that when the fan is set in motion, the motor and fan oscillate about 5 a vertical axis, so that the air blown by the fan will be directed in a wide sweep or arc instead of in a single direction. In the past, when such fans have been constructed, the oscillating means is driven directly and positively from the motor shaft so that whenever the motor shaft is in operation, the fan must oscillate, and vice versa. It very often occurs in connection with the use of such devices, that the fan guard or some part of the 15 motor body will, during its oscillation, come in contact with some object whereby its movement will be stopped. This will in turn stop the motor, due to the direct driving connection between the motor shaft and the oscillating means, and as the current continues, the motor will be burned out. I contemplate the provision of a fan wherein the oscillating mechanism and its connection to the motor shaft will be such that while during 20 normal operation of the motor, the fan will oscillate in the usual way, at the same time, if the oscillating movement is checked or stopped, the operation of the motor and fan will continue as long as current is supplied, 25 and, therefore, the likelihood of any damage being done to the motor is obviated.

One object of my invention, therefore, is to provide an oscillating fan of such construction that the motor and fan may operate although the oscillation of the fan is prevented.

Another object of my invention is to provide a frictional or slipping connection between the shaft of the fan motor and the oscillating mechanism, such that if the operation of the latter is prevented, the former will not be affected.

A still further object of my invention is 45 to provide in an oscillating electric fan, a driving connection between the fan motor and the oscillating mechanism, consisting of driving and driven disks, frictionally held together so that when the driven disk meets

driving disk will operate independently thereof.

A still further object of my invention is to provide new and improved driving connections between the fan motor and the oscillating mechanism whereby an oscillating fan may be cheaply and economically made and at the same time be reliable and efficient in its operation, the parts being so constructed that they may be readily accessible for inspection and lubrication, which are very advantageous features in a device of this character.

The invention further relates to improvements in various features of the motor itself, 65 as will be more specifically pointed out hereinafter.

To these and other ends, the invention resides in the novel features and combinations of parts to be hereinafter described and 70 claimed.

In the accompanying drawings:

Fig. 1 is a front elevational view of an oscillating fan, embodying my improvements;

Fig. 2 is a side view of the same;

Fig. 3 is a rear elevational view of the motor body and the oscillating mechanism;

Fig. 4 is a sectional view, on line 4-4 of Fig. 3;

Fig. 5 is a sectional view on line 5-5 of 80 Fig. 4;

Fig. 6 is a sectional view through the gear casing, taken on line 6-6 of Fig. 7;

Fig. 7 is a top plan view of the gear casing, 85 the cover thereof having been removed to reveal the interior mechanism;

Fig. 8 is a sectional view on line 8-8 of Fig. 7;

Fig. 9 is a sectional view on line 9-9 of 90 Fig. 4;

Fig. 10 is an underneath plan view of the driven disk of the oscillating mechanism.

Fig. 11 is a sectional view on line 11-11 of Fig. 6.

The preferred embodiment of my invention comprises a base 10 of somewhat usual form, provided at the upper portion thereof with a pair of upstanding ears 11 and 12, between which is pivotally mounted a standard 13, upon the pivot screw 14. Upon the 100

end of the pivot screw is threaded a wing nut 15, by which the ears 11 and 12 may be clamped against the flat sides of the lower end 16 of the standard to secure the fan in adjusted tilted positions relatively to the base.

The motor casing preferably consists of front and back end members 18 and 19, and an intermediate section 20, all of which parts are preferably stamped from sheet metal and held together by bolts 21, shown more especially on Figs. 2 and 3, which pass through these three parts and also through the field core 22, so as to hold the parts of the motor casing and the field core in assembled relation. The field winding is shown at 23 and may be of any preferred type.

The end sections 18 and 19 of the motor casing, are provided with perforations at their central portions for the passage therethrough of the motor shaft, and about these perforations extend outwardly, as shown at 25 and 26, to provide housings for bearing members 27 and 28. These bearing members are held in place by inner bearing caps 29 and 30, secured by the screws or rivets 31 and 32, at the interior of the casing.

As shown more especially in Fig. 6, the bearing members 27 and 28 comprise substantially spherical members flattened at their poles, and provided with central perforations 33 for the passage of the motor shaft. They are also provided with annular grooves 34 formed in a plane at substantially right angles to the motor shaft, within which a lubricant wick may be disposed. At the upper side, as shown at 35, this annular groove is sufficiently deep to communicate with the motor shaft opening 33, so as to furnish the lubricant between the bearing member and the motor shaft.

The motor shaft 40 carries the armature 41 in such a position that the latter is properly located relative to the field magnets, and this shaft projects at both ends from the motor casing. Upon its front end are secured the fan blades 42 in the usual manner. Also secured adjacent the front end of the shaft but within the motor casing is the commutator 43, in contact with which are the usual brushes housed in chambers covered by the caps 44 and 45, shown in Fig. 1. A sleeve 46 surrounds the rear end of the shaft and abuts a bearing member 28 to prevent excess longitudinal play of the shaft within the housing.

The middle section 20 of the motor casing is provided at its lower end with depending ears 47 and 48, by which the motor casing is secured to a bearing block 49, by means of a bolt 50, passing through an opening in the block and registering openings in the ears 47 and 48. The bolt 50 also passes through a perforation in the upper end of a pin 51 re-

ceived within a central opening 52 in the bearing block, so as to secure this pin to the block and motor casing. The body of the pin, which projects from the block 49, is received in the bore 53 of the standard 13, and is secured for rotating or oscillating movement therein by means of a screw 54 passing through the standard and entering an annular channel 55 in the pin. It will be apparent, therefore, that with this construction the motor casing and standard 13 may be tilted about the pivot 14, and in addition the motor casing may be rotated relatively to the standard 13, about a vertical axis.

At the rear end of the motor casing is secured a gear housing 60 by the same screws 32 which hold the bearing cap 30 in place. This gear casing is provided adjacent its lower side with a bearing boss 61, and is left open at its upper side to be covered by a removable cap 62.

The rear end of the motor shaft extends into this gear housing and is provided with worm threads 63 thereon, which engage a worm wheel 64, secured to a sleeve shaft 65 rotatably mounted upon a stud 66, secured in the lugs 67 and 68, formed integrally with the gear housing. As shown in Fig. 8, the stud 66 is inserted from the exterior of the housing, through a bore in the lug 68, and held in place by the screw 69, the remote end of the shaft being seated in a recess in the lug 67.

The sleeve 65 is provided adjacent the lug 67 with worm teeth 70, which engage the teeth of the worm wheel 71, secured to the vertical shaft 72, which is rotatably mounted in the bearing boss 61. The stud 66 is provided with a shoulder 73, which contacts with the side face of the worm wheel 64, and tends to urge the sleeve shaft 65 against the lug 67 so as to maintain the worm 70 in proper relation with the worm wheel 71.

Upon the lower end of the shaft 72 is secured a driving disk 73^a, provided with a central perforation 74, threaded to receive the threaded end of the shaft 72, and also the threaded end 75 of a screw 76. The body of this screw is considerably larger than the threaded end 75, and abuts against the lower surface of the driving disk 73^a. This screw is received in a counter bored recess 77, in a driven crank disk 78. A coil spring 79 mounted in the counter bore of this recess reacts between the head of the screw and the lower shoulder 80 of the counter bore to urge the driven disk or crank 78 toward the driving disk 73^a. Between these two disks is positioned a fibre washer 81, through which the body of the screw 76 passes. It will be seen that the spring 79 tends to hold the driven disk 78 in tight contact with the fibre washer, and likewise, the latter in tight contact with the driving disk 73^a. In this manner, a frictional driving connection is pro-

vided between these two disks which under ordinary operating conditions is sufficiently strong and positive to cause the disk 78 to be driven synchronously with the disk 73^a. If, however, the disk 78 meets unusual or strong resistance, the friction between the fibre washer and the disks will not be sufficient to overcome such resistance or stop the motor and will allow the driving disk to operate independently of the driven disk.

On the standard 13 is provided a projecting lug 84, to which is pivoted a link 85, pivoted in turn at its other end to the driven disk 78 by means of the screw 86, the pivot point being eccentric to the axis of rotation of this disk. It will be apparent that when the driven disk 78 rotates, the fan and the motor casing will be caused to oscillate with respect to the standard 13 and the base 10, due to the action of the link 85. However, if the fan guard or some portion of the motor body contacts with some object, so as to prevent the oscillating movement, the driven disk 78 will remain at rest without interfering with the rotation of the motor shaft and fan.

The fan blades may be protected by a wire guard 87 of any usual or preferred form.

While I have shown and described herein a novel form of bearing and certain improvements relative to the means for mounting the parts of the motor within and by a sheet metal casing and on a base or other supporting member, I do not claim the same herein since these improvements have been made the subject matter of my co-pending applications for an electric fan, Serial No. 248,655, filed January 23, 1928, and an electric motor, Serial No. 349,046, filed March 22, 1929.

While I have shown and described a preferred embodiment of my invention, it is to be understood that it is not to be limited to all the details shown, but is capable of modification and variation within the spirit of the invention and within the scope of the appended claims.

What I claim is:

1. In an electric fan, an electric motor, a base upon which said motor is mounted to oscillate, and means to oscillate the motor comprising a shaft rotated from the motor shaft, a disk mounted on said shaft, a screw having an enlarged head secured to the under side of said disk, a second disk provided with a counter-bored recess to receive said screw, a spring within said counter-bore and acting between the lower shoulder thereof and the head of the screw to urge the second disk toward the first, a friction washer between said disks, and a link having one end pivotally connected to a stationary part of the fan, and the other end having a pivotal connection with the second-named disk, the last-named connection being eccentric with respect to the axis of rotation of the second-named disk.

2. In an electric fan, an electric motor comprising a casing, a gear housing secured at one end thereof and carrying a depending bearing boss, a shaft rotatably mounted in said boss and driven from the motor shaft, a driving disk carried by the lower end of said shaft, and a crank disk supported by the shaft and held in frictional driving relation with said driving disk.

3. In an electric fan, a stationary base, an electric motor mounted for oscillatory movement on said base, a vertical rotatable shaft driven from the motor shaft, a driving disk carried on the lower end of the rotatable shaft, a disk supported by the rotatable shaft and having frictional driving relation with the driving disk, a crank pin on the second named disk, and a link having one end received on the crank pin and the other end mounted on the stationary base.

4. In an electric fan, a stationary base, an electric motor mounted for oscillatory movement on said base, a vertical rotatable shaft driven from the motor shaft, a driving disk carried on the lower end of the rotatable shaft, a disk supported by the rotatable shaft and having frictional driving relation with the driving disk, a crank pin on the second named disk, and a link having one end received on the crank pin and the other end mounted on the stationary base, and means for resiliently urging the second named disk into frictional driving relation with the driving disk.

5. In an electric fan, a stationary base, an electric motor mounted for oscillatory movement on said base, a vertical rotatable shaft driven from the motor shaft, a driving disk carried on the lower end of the rotatable shaft, a disk supported by the rotatable shaft and having frictional driving relation with the driving disk, a crank pin on the second named disk, and a link having one end received on the crank pin and the other end mounted on the stationary base, and means for resiliently urging the second named disk into frictional driving relation with the driving disk, said last named means including a screw mounted in the first named disk in axial alignment with the rotatable shaft, and a spring received on said screw and engaging the second named disk.

In witness whereof, I have hereunto set my hand this 27th day of July, 1926.

JOHN LANZ.
